UNITED STATES PATENT OFFICE.

LUDWIG CUBELIC, OF CHARLOTTENBURG, GERMANY, ASSIGNOR TO GENERAL ELECTRIC COMPANY, A CORPORATION OF NEW YORK.

GOVERNING MECHANISM FOR TURBINES.

1,093,116.

Specification of Letters Patent. Patented Apr. 14, 1914.

Application filed July 30, 1913. Serial No. 781,969.

To all whom it may concern:

Be it known that I, LUDWIG CUBELIC, a subject of the King of Prussia, residing at Charlottenburg, Germany, have invented 5 certain new and useful Improvements in Governing Mechanisms for Turbines, of which the following is a specification.

The present invention relates to governing mechanisms for elastic fluid turbines 10 and its object is to improve their construction by causing them to maintain more nearly uniform speed of the turbine from no load to full load. Such a result is especially desirable when the turbine is used to drive 15 an electric generator whose periodicity of voltage varies with the speed. In an ordinary speed governor having centrifugally acting weights and a spring acting in opposition thereto the sleeve or other part moved by the 20 joint action of the weights and springs has a considerable travel; in other words, the sleeve has a different position for different loads and speeds. This peculiarity of operation is troublesome when the turbine drives an electric generator, and compels 25 constant watchfulness on the part of the station attendants to correct for changes in periodicity or fluctuation in voltage arising therefrom. This correction is usually 30 accomplished by the attendant making some supplementary regulation at the switch-board or changing the tension of the spring means at the governor which opposes the action of the weights.

35 In a steam turbine, any variation in load is accompanied by a corresponding change in the high pressure stage or stages and in the same sense. I utilize this fact in my improved mechanism and cause said pressure 40 changes to act automatically on the speed governor in a manner to change the effective action of its main spring.

In the accompanying drawing is shown a multi-stage turbine and governing mechanism 45 illustrating one of the embodiments of my invention.

1 indicates a multi-stage turbine of any desired character to which steam is admitted from the main 2. Between the main and 50 turbine is a regulator such as a nozzle or throttle valve 3. A centrifugal speed governor 4 driven by the turbine is provided for controlling the regulator. The regulator is actuated by a steam or hydraulic 55 motor comprising a cylinder 5 and piston

6, the latter being connected to the regulator. Fluid is admitted to the motor by a pilot valve 7 which is connected to the governor lever 8. One end of the lever is connected to an extension of the piston rod and forms 60 a part of a follow-up device as is well understood, the other end being connected to the governor sleeve or collar 9. The pilot valve is mounted in a casing 10 and below it is a coiled compression spring 11 which rests 65 on the upper end of a differential piston 12 located in the cylinder 13. Under the piston is a compression spring 14 that tends at all times to raise it. The chamber under the piston is connected to atmosphere or it 70 may be connected to vacuum if desired.

The chamber above the enlarged piston is connected to a stage of the turbine, preferably the first because the changes in pressure are more pronounced therein than in 75 the later stages by the pipe 16. The spring 14 tends to raise the pilot valve 7 and through it act on the governor lever and the spring 15 of the governor. As the differential piston changes its position up or down 80 it effects a change in action of the speed governor by changing the effective action of the governor spring.

So long as the load on the turbine remains uniform, no variation of pressure occurs in 85 its first stage, and the tension of the spring 14 is balanced by the steam acting upon the upper surface of the piston 12. But if the load on the turbine decreases, and the speed of the turbine increases, the governor balls 90 rise, compressing the spring 15 and lifting the valve 7 to admit fluid pressure above the piston 6 to close the throttle valve 3. The decrease in load is, however, accompanied by a corresponding drop in the steam pressure 95 in the first stage of the turbine. The tension of the spring 14 is therefore partially relieved by the lessening of the steam pressure on the piston 7, and said piston tends to rise and exert an upward pressure on the sleeve 100 9 of the governor through parts 11, 7, 8 and 9 which largely counterbalance the increased downward thrust of the governor spring 15. When the load on the turbine increases, the effect is the reverse, the spring 14 being compressed and relieving the tension on the spring 11 and hence decreasing the opposition to the governor spring 15.

In the ordinary type of governor the amount of compression of the spring 15 is 110

determined solely by the position of the weights and hence of the speed of the machine. Generally speaking the weights have a shorter movement for a predetermined speed change in the lower range of operation than in the high due to the arrangement of the weights with respect to their fulcra and spring. In my improved construction the spring 11 acts in opposition to the spring 15, and the amount of this opposition is determined by the load changes in response to the pressure in the first stage. This has the effect of modifying the action of the parts in that the governor will respond more quickly to a speed change and hence more quickly adjust the regulator for the new load condition. In other words, the governor can be made to work over a smaller speed range from no load to full load than heretofore, and will more quickly respond to load changes.

In accordance with the provisions of the patent statutes, I have described the principles of operation of my invention, together with the apparatus which I now consider to represent the best embodiment thereof; but I desire to have it understood that the apparatus shown is only illustrative and that the invention can be carried out by other means.

What I claim as new and desire to secure by Letters Patent of the United States, is:

1. In combination, an elastic fluid turbine, a spring-loaded speed governor, a regulator for the turbine controlled by the governor, and automatic means for varying the effective action of the spring on the governor in response to varying loads on the turbine.
2. In combination, an elastic fluid turbine, a spring-loaded speed governor, a regulator for the turbine controlled by the governor, a spring acting on the governor in opposi-

tion to its spring, and a device responsive to load conditions on the turbine for changing the tension of the second mentioned spring.

3. The combination with an elastic fluid turbine, of a spring-loaded speed governor, and means controlled by the pressure in a stage of the turbine for opposing the tension of the spring.

4. The combination with an elastic fluid turbine, of a spring-loaded speed governor, a spring opposing the tension of the governor spring, and means responsive to variations in the pressure in a stage of the turbine for controlling the action of said opposing spring.

5. The combination with an elastic fluid turbine, of a spring-loaded speed governor, a spring opposing the tension of the governor spring, a piston acting upon the opposing spring, and means for subjecting said piston to fluid pressure from the first stage of the turbine so that the action of said opposing spring varies with variations in the stage pressure.

6. The combination with an elastic fluid turbine, of a throttle valve, a motor for operating it comprising a pilot valve, a spring-loaded speed governor, a lever therefor fulcrumed on said pilot valve, a differential piston acting against one end of said valve, a spring abutting against the under side of said piston and acting against the tension of the governor spring, and a pipe leading from a stage of the turbine to the upper side of said piston.

In witness whereof, I have hereunto set my hand this 15 day of July, 1913.

LUDWIG CUBELIC.
